UNITED STATES PATENT OFFICE.

DENNIS C. BURDICK, OF MILTON, WISCONSIN.

COMPOUND METAL-WORKING MACHINE.

SPECIFICATION forming part of Letters Patent No. 249,297, dated November 8, 1881.

Application filed August 25, 1881. (Model.)

To all whom it may concern:

Be it known that I, DENNIS C. BURDICK, of Milton, in the county of Rock, and in the State of Wisconsin, have invented certain new and useful Improvements in Punch and Shearing Machines; and I do hereby declare that the following is a full, clear, and exact description thereof, reference being had to the accompanying drawings, and to the letters of reference 10 marked thereon, making a part of this specification.

This invention relates to machines which are designed for punching and shearing metal; and it consists, essentially, in a novel construction and arrangement of the several parts of 15 the machine, whereby I obtain great strength and durability, and also great facility in the manipulation of the different kinds of work, as will be fully understood from the following 20 description.

In the annexed drawings, Figure 1 is an elevation of one side of my combined shearing and punching machine. Fig. 2 is a central section taken longitudinally and vertically 25 through the machine. Fig. 3 is a perspective view of the adjustable gage.

Similar letters of reference indicate corresponding parts in the three figures.

The letter A designates the horizontal bed 30 or bench, on which is secured, by means of bolts *a a*, the strong frame B. This frame B is composed of two vertically and centrally divided cheeks or parts rigidly bolted together, as shown.

C designates a strong lever, which is fulcrumed between the two ears *a* by means of a bolt, *b*, and is guided at and near its rear end between the two standards *c* of the frame. This lever is made broad and strong, and its 40 longest arm is connected to the enlarged segment-shaped end of a hand-lever, C', by means of an arc-shaped link, *d*. The lever C' is fulcrumed to said standards *c* by means of a transverse bolt, *e*, which, with the bolt *b*, connects 45 the upper parts of the frame B together.

Lever C' extends forward over the lever C, as shown, and is in a convenient position to be operated by an attendant at the front part of the machine.

The front or short arm of the lever C is recessed, so as to leave a depressing-shoulder, *e'*, and a raising-shoulder, *e''*, between which is a lug, *f*, formed on the back of a punch-block, D, in which punch-block is combined a removable punch, *g*.

The movement of lever C imparts a vertical motion to the punch and its block, which latter is guided in grooves formed in the front end of frame B.

The die-block, which is lettered *h*, is fitted 60 into a dovetail groove made in the portion *a'* of said frame. There is ample space left above the die *h* for the manipulation of the metal to be punched.

The die *h* is confined in its place below the 65 punch by means of a set-screw, *i*, and beneath this die is a passage for the free escape of the punchings.

Back of the punch-die *h* is a long passage, 70 in which is applied an adjustable gage, F, which is held in place by means of a set-screw, *j*. On each side of the punch I apply a curved plate or clearer, *k*, for clearing the punched metal from the punch as it ascends.

The two clearers are secured to the frame B, 75 and should be adjustable.

G designates an oblong slot, which is made through one cheek of frame B opposite an oblong passage, *l*, through the lever C, to the upper part of which passage *l*, and secured to 80 said lever, I apply a knife or shear, H, so that it will cut with a shear-stroke against the edge of a blade, H', secured to the cheek of the frame B, and shown in Fig. 2. These shears are for cutting flat iron. Below the said shears 85 a number of holes, *n*, are made transversely through one of the cheeks of frame B, which holes terminate in a shear-plate secured to the back of said cheek. The said holes are of different sizes, for receiving through them 90 several different diameters of gages of round rod metal, which is cut by the scalloped-edge shear-blade N, fixed to the lever C. (Shown in Fig. 2.)

Having described my invention, I claim— 95

1. The combination, with the frame B, the great lever C, its shoulders *e'* *e''*, punch D, its lug *f*, hand-lever C', curved connecting-link *d*,

and the adjustable and removable gage F, provided with a set-screw, j, substantially as described.

2. The frame B, constructed with a guiding-slot, G, in combination with the great lever C, its shear-blades H N, oblong passage l, perforations n through said frame, lever C', and link d, arranged as shown and described.

In testimony whereof I have affixed my signature, in presence of two witnesses, this 28th day of July, 1881.

DENNIS C. BURDICK.
